BIMETALLIC FLOOR STRIP

Filed July 1, 1929

Pasquale Galassi.

BY
GEO. M. SACCIO, Esq.
ATTORNEY

UNITED STATES PATENT OFFICE

PASQUALE GALASSI, OF NEW YORK, N. Y.

BIMETALLIC FLOOR STRIP

Application filed July 1, 1929. Serial No. 375,053.

This invention relates to dividing strips for terrazzo and similar floors and more particularly refers to improvements in dividing strips of the type where economy of cost is obtained without impairing the appearance and serviceability of the product.

Terrazzo, granolithic, stucco and similar floors usually comprise a lower or foundation bed made of concrete or cement or mortar or other suitable material, and an upper or finishing layer generally consisting of a mixture of marble chips and cement, by means of which a good durable surface may be obtained as well as pleasing designs and color effects of a practically unlimited variety.

The upper layer which is generally placed in position after the foundation layer has been allowed to harden to a sufficient degree of consistency, is generally divided into a number of panels or units in a predetermined arrangement, which are obtained by outlining the desired design by means of dividing strips placed on or through the foundation layer.

These strips generally consist of relatively thin and wide metal bars set on edge, said bars having their upper edges flush with the surface of the floor, defining the desired design.

Said bars are generally provided with anchoring and positioning means insuring a firm binding action between the strips of the materials of which the floor is composed; the positioning means furthermore serving as a gauge determining the line of separation between the lower and the upper layer.

These bars are generally made of relatively soft metal such as brass for instance, the wearing qualities of which are approximately equal to those of the floor itself; and according to the nature of the floor and of the design to be produced, the dividing strips may be of various thicknesses and lengths.

Relatively thin strips may readily be obtained out of sheet metal, and are suitable for floors of moderate size; however, relatively large floors, or floors composed of relatively large units, call for strips having sufficient rigidity to withstand the lateral pressure of the material without bulging when the floor is laid.

These heavier strips are also generally made out of sheet metal but brass being expensive material, their use materially increases the cost of the floor. At times the ornamental features are such as to require extra thick metallic strips showing through the material, and in these cases, the cost is still higher.

It is therefore important to save as much as possible in the cost of the materials employed and I have accordingly produced a type of dividing strip in which the upper section is made out of a bar of brass or other suitable material while the lower section is made of less expensive material such as for instance, sheet steel.

Broadly, the idea of using two different metals, one more expensive for the upper portion and one less expensive for the lower portion of the strip, is not new, strips of this character having been described and claimed by me in three other patents previously granted to me; Nos. 1,718,041; 1,697,683; 1,715,193. However, the strips described in said patents comprise each an upper and a lower section connected to each other by means of dovetailed joints.

I have found in practice that the design and mode of construction of bimetallic strips may be simplified without impairing their usefulness, at the same time effecting considerable economies in the cost of the manufacture of tools required.

The primary object of this invention is to provide dividing strips for terrazzo and similar floors having an upper and a lower section, the lower section being made of relatively inexpensive material, and being connected to the upper section by means of riveting or similar operations.

Another object of the invention is to provide a novel and improved arrangement of bimetallic strip composed of two sections, which may be of the same or of different thicknesses.

A further object of the invention is to provide a dividing strip for terrazzo or similar floors composed of two sections joined to each other, said section being adapted to be produced by readily available methods and means

of manufacture and lending themselves to standardization although upper sections of various widths may be used.

Other objects and advantages of the present invention will more fully appear as the description proceeds and will be set forth and claimed in the appended claims.

Various embodiments of my invention are illustrated in the accompanying drawings in 10 which:

Fig. 1 is a fragmentary view in perspective of a strip embodying my invention in one of its possible forms;

Figs. 2 and 3 are similar views of strips in 15 different designs also embodying my invention;

Fig. 4 is a fragmentary plan view of a bar from which two upper sections of the type shown in Fig. 3 may be obtained;

20 Fig. 5 is an end elevation thereof;

Fig. 6 is a fragmentary plan view of a metal strip from which two lower sections of the type illustrated in Fig. 3 may be obtained;

25 Fig. 7 is a fragmentary view in perspective of a still different type of strip in which the two sections are secured to each other by means of through tongue and slot joints;

Fig. 8 is a fragmentary side view in elevation of the upper section of said strip;

30 Fig. 9 is a cross sectional view of the same;

Fig. 10 is a fragmentary side view in elevation of the lower section of the strip shown in Fig. 7;

35 Fig. 11 is a fragmentary side view in elevation of another strip composed of two sections joined by through tongue and slot joints;

Fig. 12 is a cross sectional view of the same; and

40 Fig. 13 is a plan sectional view of the same;

Fig. 14 is a cross sectional view of the strip and floor.

The strip illustrated in Fig. 1 comprises an upper section 20 formed with a relatively thick upper portion 21 having an uninterrupted upper edge or surface 22 and a rib portion 23 depending therefrom. To said upper section which may be made of brass or other suitable material is connected a 45 lower section 24 which is made of steel or other relatively inexpensive but strong material, by means of rivets such as 25 passing through the upper part of section 24 and rib portion 23 of the upper section.

50 The lower section is preferably provided with anchoring and positioning means of any suitable description, for instance, in the form of ears 26 struck off and laterally bent from the body of said lower section.

55 The same type of connection may be used between a relatively thin upper section 27 and a relatively thin lower section 28 as shown in Fig. 2, the inner edges of said sections being overlapping a sufficient distance 60 for the insertion of rivets 29. In said Fig. 2

I show the anchoring and positioning means in the form of open shape cup members 30 struck off and laterally offset from the body of the lower section.

This type of anchoring and positioning means is preferable to that shown in Fig. 1 because the strip is strengthened rather than weakened thereby.

65 In Fig. 3 I illustrate a strip to a certain extent similar to that shown in Fig. 1, with the difference that both the upper and the lower section are notched so as to permit saving of material in the process of manufacture.

The upper section 31 is composed of a relatively thick upper part 32 having an uninterrupted upper edge 33, and a plurality of evenly spaced relatively thin lug members 34 depending therefrom. Said lug members are separated by intervening notches 35 which are preferably of the same length as the lugs; 70 by virtue of this construction, it is possible to obtain two upper sections out of a bar composed of two thick edge portions 32', 32'' joined by a rib section 34', the section of said portions 32' corresponding to the section of part 32, and the section of rib 34' corresponding to the section of lugs 34.

75 Said bar may be cut longitudinally in a zig-zag outline as shown in Fig. 4, so that one half of the material which would otherwise be required to produce a solid rib portion 34 will be saved.

In a similar manner, the lower section 36 is composed of a lower strip portion 37 having an uninterrupted lower edge 38, evenly spaced lugs such as 39 upwardly projecting therefrom. Said lugs 39 are spaced to register with lugs 34, so that their upper edge portion may overlap said lugs a sufficient distance to permit the insertion of rivets 40.

80 In this manner two lower sections 36', 36'' may be obtained by cutting a single strip the width of which is equal to the height of one lower section plus the height of lower edge portion 37 as shown in Fig. 6.

85 Lugs 39 are preferably provided with anchoring or positioning means such as ears 41, although it must be observed that the positioning action may be fulfilled by the lower edge and the upper section of the strip, while the ears or other anchoring means may be formed at a lower level if desired.

90 Instead of being connected by means of rivets the two sections may be connected by providing one of said sections with slots and the other one with tongues which may be inserted through said slots and bent over so as to form a permanent connection therebetween.

95 For instance, the strip shown in Figs. 7 to 10, is composed of an upper section 42 comprising, like the strip of Fig. 3 an upper relatively thick part 43 and a plurality of evenly

spaced relatively thin lugs 44 depending therefrom.

Said lugs are each provided with a longitudinal through slot 45 through which may 5 be inserted tongues 46 projecting from and bent laterally of upper edge 47 of the lower section 48.

After said tongues have been inserted through slots or openings 45 they are 10 bent downwardly and inwardly about the lower part of the corresponding lugs 44, as shown at 49 in Fig. 7, and the two sections are thus permanently connected to each other.

The lower edge 50 of the lower section may 15 be notched as shown at 51, in correspondence of tongues 46 in order to permit the tongues of one unit to be obtained out of notches produced in a previously cut unit, as Fig. 10 clearly shows.

20 Also in this case the tongues and notches 51 are spaced sufficiently to form relatively long lugs 52, so that anchoring or positioning means or both such as ears 53 may be struck off the lower section and bent laterally 25 thereof.

While tongues 46 are shown projecting from the upper edge of the lower section it is obvious that said tongues may also be struck off the body of said lower section; and 30 it is also obvious that a positive connecting action may also be had if the tongues are bent in a longitudinal direction instead of being bent downwardly as shown in Fig. 7.

For instance, in Figs. 11, 12, 13, 53 designates the upper section which is provided with spaced openings 54 through which may be inserted tongues 55 struck off the body of the lower section 56, the outer end of said tongue being bent rearwardly as shown at 57 40 so as to connect the two sections together.

In Fig. 14, I show a strip of the type illustrated in Fig. 1 in position. In said figure, 57 designates the lower layer or bed of the floor laid on the floor foundation 58, and 59 designates the upper layer, the upper section 60 of the strip having its upper edge 61 flush 45 with the upper surface of the floor.

My invention may be embodied in strips of 50 various other designs, as will be understood; the drawings will therefore be understood as being intended for illustrative purposes only and not in a limiting sense. Accordingly, I reserve myself the right to carry my invention into practice in all those ways and manners which may enter, fairly, into the scope 55 of the appended claims.

I claim:

1. A floor strip of the character described, 60 comprising an upper section and a lower section, said upper section having a longitudinally extending top portion with an uninterrupted upper edge, and a plurality of spaced lugs depending therefrom, said lugs 65 being provided with through openings, and

means passing through said openings, connecting said sections to each other.

2. A floor strip of the character described, comprising an upper section and a lower section, said upper section being provided with 70 a plurality of longitudinally spaced openings, and means integral with said lower section, passing through said openings, connecting said sections to each other.

3. A floor strip of the character described, 75 comprising an upper section and a lower section, said upper section having a longitudinally extending top portion with an uninterrupted upper edge, and a plurality of spaced lugs depending therefrom, said lugs being 80 provided with through openings, and means integral with said lower section, passing through said openings, connecting said sections to each other.

4. A floor strip of the character described, 85 comprising an upper section and a lower section, said upper section having a longitudinally extending top portion with an uninterrupted upper edge, at least one of said sections being provided with a plurality of 90 longitudinally spaced openings, means passing through said openings, rigidly connecting said sections to each other, and anchoring means integral with and offset laterally 95 of said lower section.

5. A floor strip of the character described, comprising an upper section and a lower section, said upper section having a longitudinally extending top portion with an uninterrupted upper edge, and a plurality of spaced lugs depending therefrom, said lugs being provided with through openings, means passing 100 through said openings, connecting said sections to each other, and anchoring means integral with and offset laterally of said 105 lower section.

6. A floor strip of the character described, comprising an upper section and a lower section, said upper section being provided with a plurality of longitudinally spaced openings, means integral with said lower section, passing through said openings, connecting said sections to each other, and anchoring means integral with and offset laterally of said lower section. 110

7. A floor strip of the character described, comprising an upper section and a lower section, said upper section having a longitudinally extending top portion with an uninterrupted upper edge, and a plurality of spaced lugs depending therefrom, said lugs being provided with through openings, means integral with said lower section, passing 120 through said openings, connecting said sections to each other, and anchoring means integral with and offset laterally of said lower section. 125

8. A floor strip of the character described, comprising an upper section and a lower section, said upper section being provided with 130

a plurality of longitudinally spaced openings, and tongues extending from the upper edge of said lower section, passing through said openings, connecting said sections to each other.

5 9. A floor strip of the character described, comprising an upper section and a lower section, said upper section being provided with a plurality of longitudinally spaced openings, and tongues extending from the upper edge of said lower section, passing through said openings, connecting said sections to each other, the lower edge of said lower section being formed with notches symmetrical with said tongues.

10 10. A floor strip of the character described, comprising an upper section and a lower section, said upper section having a longitudinally extending top portion with an uninterrupted upper edge, and a plurality of spaced lugs depending therefrom, said lugs being provided with through openings, and tongues extending from the upper edge of said lower section, passing through said openings, connecting said sections to each other.

15 11. A floor strip of the character described, comprising an upper section and a lower section, said upper section being provided with a plurality of longitudinally spaced openings, tongues extending from the upper edge of said lower section, passing through said openings, connecting said sections to each other, and anchoring means integral with and offset laterally of said lower section.

20 12. A floor strip of the character described, comprising an upper section and a lower section, said upper section having a longitudinally extending top portion with an uninterrupted upper edge, and a plurality of spaced lugs depending therefrom, said lugs being provided with through openings, tongues extending from the upper edge of said lower section, passing through said openings, connecting said sections to each other, and anchoring means integral with and offset laterally of said lower section.

25 13. A floor strip of the character described, comprising an upper section and a lower section, said upper section having a longitudinally extending top portion with an uninterrupted upper edge, and a plurality of spaced lugs depending therefrom, said lugs being provided with through openings, tongues extending from the upper edge of said lower section, passing through said openings, connecting said sections to each other, and anchoring means integral with and offset laterally of said lower section, the lower edge of said lower section being formed with notches symmetrical with said tongues.

PASQUALE GALASSI.

DISCLAIMER

1,813,736.—*Pasquale Galassi*, New York, N. Y. BIMETALLIC FLOOR STRIPS. Patent dated July 7, 1931. Disclaimer filed December 28, 1932, by the patentee.

“I disclaim from the scope of claims 2, 4 and 6 that type of floor strip which is composed of an upper and a lower section permanently connected to each other, in which the longitudinally spaced openings provided in at least one of said sections, and the means passing through said openings rigidly connecting said sections to each other are produced simultaneously by partially punching and forcing out laterally burrs or lugs from the adjoining thicknesses of metal, forming spaced prong members laterally offset from the body of the strip.”
